DISPLAY PACKAGE

George E. Damrow, Glen Ridge, N. J., assignor to
Pie-Pak Company, Inc., Hoboken, N. J.

Application September 21, 1939, Serial No. 295,850

6 Claims. (Cl. 206—44)

My invention relates to display packages and more particularly to such packages for individual cakes, pies, and the like. The invention will be described as applied to cakes, but the general applicability will be understood from such description.

Serviceable and satisfactory packages of this general type heretofore provided have been expensive to manufacture, and in some cases have been complicated in assembly, but for the most part the packages heretofore intended for these uses have not been practical. Such packages must be at all times attractive; they must satisfactorily display the merchandise to the view of the customer; they must be sturdy so as to withstand the repeated handlings in the bakery, in deliveries to and from the retail store and in the store, and, preferably, they should be capable for re-use by the customer until the contents of the package are consumed. Additionally, such packages must protect the goods from dirt and dust, as well as from damage while the package is being handled.

It is the object of my invention to provide a package of the above indicated type which will overcome the above disadvantages and meet the foregoing requirements for such packages in a thoroughly practical manner.

It is another object of my invention to provide a package that is especially useful with cakes, pies, and the like, that are of considerable diameter and height so that the appearance thereof will be preserved.

It is another object of my invention to provide a package of the above indicated type which comprises only a few parts that may be shipped to the bakery in flat or "knockdown" condition requiring a minimum of shipping and storage space.

It is a further object of my invention to provide a package of the above indicated type which will require only a few simple and fool-proof assembly operations by unskilled workers to accomplish commercially satisfactory packages, and without the use of any mechanical apparatus.

It is a still further object of my invention to provide a package for the above purposes which does not require the use of glue, adhesives or other materials which might contaminate the food products or come apart after the packaging of the goods is completed.

It is an even further object of my invention to provide a package of the above character in which the package may be partially completed and stacked ready for insertion of the cake, whereupon the package is completed by a simple operation.

Other and further objects of my invention will be apparent from this specification taken in con-

junction with the accompanying drawing, wherein—

Figure 1 is a side elevation, with parts broken away and parts sectioned, of a package constructed according to this invention;

Fig. 2 is a vertical section of a partially assembled package ready for insertion of the cake;

Fig. 3 is an exploded view illustrating the assembly of the cake in formation of the package; and

Fig. 4 is a plan view of the outer band of the package, as it is shipped to the bakery.

Referring to the drawing, in which is shown the best form I have now contemplated applying my invention, the bottom of the package is closed by a plate 11 which supports the cake. In this illustration, the plate is a flat, circular board cut from ordinary corrugated board in extensive commercial use in which the corrugated portion is covered by top and bottom sheets of paper 12 and 12a, respectively. If desired, these sheets may be of any special paper required for the particular foodstuffs to be packaged. Of course, any other material may be used for the plate 11, and the same may have any required form, such as the ordinary pie plate.

Supported upon the plate is a frusto-conical collar or inner band 13 the diameter of the base of which is such that the collar will rest on and be supported by the plate 11. It is preferred that the outside of the collar 13 substantially coincide with the perimeter of the plate 11. The collar is sufficiently tall as to extend above the top of the cake or other article to be packaged, and the top edge of the collar may be scalloped or cut out, as indicated at 14, to enable the customer to see more of the packaged article. The collar 13 is formed of a single arcuate shaped strip of fibrous material as light weight cardboard, having near one end thereof a pair of slits 15, and on its opposite end a locking tongue 16. When the strip is formed into the collar the tabs of the tongue 16 engage in the slits 15, and the ends of the strip overlap each other.

Surrounding the collar 13 is a frusto-conical outer band 17, the construction of which is shown in Fig. 4. This band is also formed from an arcuate shaped strip of cardboard and has on one end thereof a locking tongue 18 and adjacent to the other end a pair of slits 19 in which the tabs of the tongue 18 engage when the band is formed ready for assembly in the package. The lower edge of the band is provided with a plurality of separated tabs 21 which in this construction are of considerable length so that each occupies a substantial segment of the circumference of the band. The upper edge of the tabs are defined by a score line 22. The functions of these tabs will be pointed out in describing the formation and construction of the package.

In constructing the package, the operator forms the inner band or collar 13, as described. This is placed over a form 23 (Fig. 2) which is supported by a pedestal 24 with which it may be integral. The form will be of the proper diameter for the particular size package, and has tapered sides 25 upon which the collar fits. Over the top of the collar 13 is next placed a sheet of transparent paper 26, the edges of which extend well beyond the collar 13. The operator then passes the outer band, already formed, over the collar 13, and presses the same down above the collar so as to frictionally lock the edges of the transparent paper 26 between the collar and outer band, in which action advantage is taken of the action of the coincidental tapers of the collar and outer band. In this position, it will be noted that the top edge of the outer band 17 is below the scallops or cut out portions 14 of the collar 13. These sub-assemblies of the package are now ready to receive the plate containing the cake or other article. Being frusto-conical in shape, a reasonable number may be stacked in nested relation and put aside until wanted.

The operation of completing the packaging of the cake will be understood from Figs. 3 and 1. The plate 11, to which the cake has been transferred, is placed upon a block 27 and one of the above described sub-assemblies is fitted about the plate so that it closes the bottom of the package housing the cake. Then the tabs 21 are bent inwardly and upwardly with the fingers. As shown in Fig. 1, the tabs are forced back toward the inner surface of the outer band and they are of such length that the ends thereof are bent over, as indicated at 28, in engagement with the underside of the plate 11. Either in the operation of placing the sub-assembly upon the plate 11, or when turning up the tabs 21, the plate is forced into the frustum of the outer band and against the collar 13. Thus, the collar cannot slip down out of place to cause dis-assembly of the package. In the assembled position the tabs 21 also support the plate around its entire circumference so that it cannot fall out of the package. At the same time, the tabs prevent the outer band from being moved upwardly, which would loosen the frictional lock between the band, the transparent paper and the collar. When on display, the packaged cake rests upon the portion of the outer band defined by the score line 22, and the described rigid, interlocked condition of the whole package holds true even though the package may be handled at one side only.

The types of interlocks for the collar and the outer band are symbolical of various means that may be used for this purpose.

Other modifications may be made in the arrangement and location of parts within the spirit and scope of my invention, and such modifications are intended to be included in the appended claims.

I claim:

1. A display package comprising a plate, a tapered collar extending upwardly from the plate a substantial distance, a sheet of transparent paper overlying the collar and plate and extending outside the collar, a tapered outer band fitting about the collar and perimeter of the plate with the transparent paper clamped between the tapered collar and band, said band also extending below said plate and having portions

on the lower end which extend inwardly and upwardly to engage beneath the bottom of the plate adjacent its perimeter.

2. A display package comprising a plate, a separate strip of material provided with means for securing the ends together to form a tapered collar arranged to be carried by said plate, a sheet of transparent material overlying the collar and plate and extending outside the collar, another strip of material provided with means for securing the ends together to form a tapered outer band arranged to fit about the collar and perimeter of the plate and to clamp the transparent material between the band and collar, the band also extending below said plate, and means carried by the band and arranged to engage the undersurface of the plate to support the same in the package.

3. A display package comprising a plate, a strip of material provided with means for securing the ends together to form a tapered collar arranged to be carried by said plate, a sheet of transparent material overlying the collar and plate and extending outside the collar, a strip of material provided with means for securing the ends together to form a tapered outer band arranged to fit about the collar and perimeter of the plate and to clamp the transparent material between the band and collar, said band also extending below said plate and being provided with a plurality of tabs each constructed and arranged to engage a substantial portion about the margin of the undersurface of said plate.

4. A display package comprising a plate, a strip of material provided with means for securing the ends together to form a tapered collar arranged to be carried by said plate, a sheet of transparent material overlying the collar and plate and extending outside the collar, a strip of material provided with means for securing the ends together to form a tapered outer band arranged to fit about the collar and perimeter of the plate and to clamp the transparent material between the band and collar, the band also extending below said plate and the lower portion of said band being formed with a few tabs each of a size to engage a substantial portion about the margin of the undersurface of said plate and together supporting substantially the entire margin of said plate.

5. A display package comprising a plate, a tapered collar extending above the plate, a sheet of transparent material overlying the collar and extending outside the same, a tapered band fitting about the collar to clamp the transparent material therebetween, the band also extending below said plate, and means carried by the band and arranged to hold the plate pressed against the lower edge of the collar.

6. A display package comprising a plate, a tapered collar extending above the plate, a sheet of transparent material overlying the collar and extending outside the same, a tapered band fitting about the collar to clamp the transparent material therebetween and also extending below said plate, and a plurality of tabs on the lower portion of the band and arranged to force and hold the plate against the lower edge of the collar when the tabs are brought into position beneath the plate.

GEORGE E. DAMROW.
